UNITED STATES PATENT OFFICE.

CHARLES F. RITCHEL, OF BRIDGEPORT, CONNECTICUT, ASSIGNOR TO IVES, BLAKESLEE & CO., OF SAME PLACE.

DESIGN FOR A TOY FOR EXPLDING CAPS AND FULMINATES.

SPECIFICATION forming part of Design No. 12,750, dated February 7, 1882.

Application filed October 20, 1881. Term of patent 7 years.

To all whom it may concern:

Be it known that I, CHARLES F. RITCHEL, of Bridgeport, in the county of Fairfield and State of Connecticut, have originated and produced 5 a new and original Design for a Toy for Exploding Caps and Fulminates, of which the following is a specification.

My design consists in making the hand-piece of the toy in the form of a pistol or fire-arm 10 and the cap or fulminate receptacles and hammer in the form of figures resembling human beings, substantially as hereinafter particularly set forth.

The accompanying drawing is a side view of 15 a toy embodying my design.

A designates a hand-piece made in the form of a fire-arm or pistol.

B designates a cap or fulminate receptacle made in the form of a figure resembling a human being, erected on the barrel-like portion 20 of the hand-piece A; and C designates a hammer made in the form of a figure resembling the whole of a human being, adapted to rock forward, as indicated in dotted lines, and strike with its nose the figure B, forming the cap or 25 fulminate receptacle. The figure B is made to represent "Judy," and the cavity for the cap or fulminate is located in a hump on the back. The figure C represents "Punch."

The trigger D, as shown, is made in the same 30 piece with the hammer.

It will be seen that by my invention I produce a very unique and attractive toy.

What I claim as my design, and desire to secure by Letters Patent, is—

- 35 1. The design for a toy for exploding caps and fulminates, substantially as specified.
2. The design for a toy for exploding caps and fulminates, consisting of a hand-piece made in the form of a pistol or fire-arm, a cap or fulminate receptacle made to represent Judy, and a hammer made to represent Punch, substantially as specified.

CHARLES F. RITCHEL.
